UNITED STATES PATENT OFFICE.

OGLESBY ALLEN, JR., OF CHICAGO, ILLINOIS.

WASHING MACHINE.

Original application filed March 14, 1919, Serial No. 282,585. Divided and this application filed July 21, 1919. Serial No. 312,176.

To all whom it may concern:

Be it known that I, OGLESBY ALLEN, Jr., a citizen of the United States, and a resident of Chicago, in the county of Cook and State of Illinois, have invented certain new and useful Improvements in Washing Machines; and I do hereby declare that the following is a full, clear, and exact description thereof, reference being had to the accompanying drawings, and to the characters of reference marked thereon, which form a part of this specification.

This invention relates to improvements in washing machines of that general type which embraces a clothes receiving cylinder of open work construction that is contained within and is adapted to be submerged in the wash water in a tub and is adapted to be rotated continuously in one direction for bringing the wash water in which the cylinder is partially submerged in contact with the clothes in said cylinder. This feature of the construction may, however, be varied.

My invention is herein shown, as more particularly adaptable to that type of washing machine illustrated in my prior application for United States Letters Patent Serial Number 282,585, filed March 14, 1919, of which this application is a division.

The present invention relates more specifically to improvements for forcing the wash water under pressure through the clothes in the cylinder and for withdrawing the water from the tub and returning it thereto for passage through the clothes over and over again until the clothes have been cleaned.

The invention consists in the combination and arrangement of the parts shown in the drawings and described in the specification and is pointed out in the appended claims.

In said drawings,

Figure 1 is a vertical section of a washing machine embodying my invention.

Figure 2 is a plan view of the tub with the cover removed.

Figure 3 is a detail illustrating the pump and pipe connections for forcing the water into and withdrawing it from the tub.

As shown in the drawings, 10 designates the tub which may be of any suitable shape and is shown as rectangular in plan. It is provided with a bottom 11 and a removable cover 12 and is supported on legs or stands 13. 14 designates the clothes receiving drum or cylinder which is of open work con-

struction, being herein shown as made of wood and perforated in its circumferential wall. The said cylinder is provided with a hinged door 15 through which access may be had to the cylinder for the insertion and removal of the clothes, and said door is adapted to be locked closed by any suitable form of locking means 16. The cylinder may be rotatively mounted in the end walls of the tub in any suitable manner, as, for instance, by the means illustrated in my copending application for United States Letters Patent Serial Number 319,074, filed on the 22d day of August, 1919, which is also a division of my aforesaid application Serial Number 282,585. As illustrated in said latter application, said cylinder is adapted to be rotated continuously in one direction, although this feature of the construction may be varied.

18 designates a pump shown as of the rotary type which is supported on a mounting board 19 that extends between and is supported on the legs or standards 13. Said pump is driven by a motor 20, an electric motor as herein shown, that is also supported on the mounting board 19, the motor being connected to the pump through the medium of a shaft 21.

22 designates a pipe which leads from the outlet side of the pump 18 and extends horizontally therefrom beneath the tub. Said pipe continues upwardly through the bottom wall 11 of the tub as a stand pipe 23, and said stand pipe terminates at its upper end in a cross head 24 that is disposed parallel to the axis of the cylinder 14. Said cross head is arranged suitably above the axis of said cylinder and above the water level in the tub, and is provided on the cylinder side of the head with a series of spray apertures 25 which discharge at an angle downwardly and inwardly toward the cylinder. Said pipe is made of the full length of the cylinder.

26 designates a stand pipe which is located on the side of the cylinder opposite the cross or distributing head 24, and said pipe extends downwardly through the tub bottom 11 and is connected to the intake side of the pump 18. Said stand pipe 26 terminates at its upper end in a cross drain or intake head 27 which is disposed parallel to the cross head 24 and is provided with a series of inlet openings 28. Said cross head 27 is located at a level to be always sub-

merged in the body of the wash water in the tub and is preferably disposed near the level of the water in said tub.

In the operation of the machine, the clothes are placed in the cylinder and the tub is filled with wash water to about the level indicated in Figure 1. Thereafter said cylinder is rotated, as by power communicated to it through a drive shaft 29 and meshing gears on said shaft and the driving trunnion of the cylinder. The pump is by said motor 20 rotated at high speed, and the position of said cross or distributing head 24 on the stand pipe 23, connected to the outlet side of the pump, and the angle of discharge of the apertures 25 are such that the water forced by said pump through the stand pipe 24 and into the head is discharged with considerable force directly against the perforated or open work cylinder and directly on the clothes contained therein, so that the pressure of the water is utilized to drive the water through the fabric of the clothes to wash the dirt therefrom. The water, after passing through the cylinder and the clothes, is drawn through the head 27 and stand pipe 26 backwardly to the intake side of the pump. There is, therefore, maintained a circulation of water at considerable pressure and speed against the clothes in the cylinder, and the capacity of the pump is such that a substantial volume of water may be circulated in a given time so that the clothes subjected to the washing influence of the circulating wash water are rapidly cleansed. Moreover, by reason of the fact that the intake head 27 of the stand pipe 26 is located adjacent to the level of the wash water in the tub, the said intake head has the effect to produce a suction action of the water through the clothes, thereby improving the washing action of the water on the clothes. It will be observed that the intake head is located a distance above the bottom 11 of the tub, as well also above the lowermost part of the drum 14. By reason of this arrangement of the parts, and because of the fact that said intake head is located near the level of the wash water in the tub the body of water at the bottom of the tub is relatively quiescent, with respect to the water discharged from the spray head 24, so that, thereby heavy particles dislodged from the clothes can settle into this relative quiet body of water and is not again repassed through the pump. The inner surface of the cylinder may be provided with a number of longitudinal ribs 30 which have the effect to lift the clothes on the rising side of the cylinder and to throw them inwardly toward the center of the cylinder, and this manipulation of the clothes facilitates the passage of the wash water therethrough.

The said motor may be connected to and dis-

connected from the pump by the means illustrated in my aforesaid prior application Serial Number 282,585 but this feature of the construction is not herein illustrated.

I claim as my invention:

1. A washing machine comprising a tub, a perforated clothes drum therein mounted to turn on a horizontal axis, with means to operate it, and means to forcibly discharge wash water against the drum and through the clothes therein and to forcibly withdraw the wash water from the drum and to again direct it against the drum, said means embracing a pump and a discharge and an intake head connected to said pump and located respectively on opposite sides of the drum and in different horizontal planes, the discharge above and the intake below the level of the axis of said drum. 70

2. A washing machine comprising a tub, a perforated clothes drum therein mounted to turn on a horizontal axis, with means to operate it, a circulatory system for water embracing a pump, and a discharge pipe and return pipe, the outlet end of said discharge pipe being horizontally located above the axis of the drum and adapted to direct the water forcibly onto and through the drum, and the intake end of the return pipe being horizontal and adapted to be submerged in the wash water near the level of the water and located above the bottom of the floor and the lowermost part of the drum and directly connected to the intake of the pump. 90

3. A washing machine comprising a tub, a perforated clothes drum therein mounted to turn on a horizontal axis, with means to operate it, a stand pipe extending upwardly through the bottom of the tub and provided at its upper end with a horizontal perforated spray head parallel to the axis of the drum, said spray pipe being substantially the length of the drum and located above the drum axis and having spray openings directed toward the drum axis, a high speed pump to the outlet of which said stand pipe is connected, and a draw-off pipe having a horizontal perforated head below the axis of said drum and submerged in the water in the tub at that side of the drum opposite and parallel with said spray head and connected to the intake side of said pump. 110

4. A washing machine comprising a tub, a perforated clothes cylinder therein mounted to turn on a horizontal axis, with means to rotate it, a spray head parallel with the axis of the tub and located a distance above said axis and provided with downwardly and inwardly inclined spray openings, a pump, to the outlet side of which said spray head is connected, a horizontal draw-off pipe connected to the intake side of the pump and provided at its end within the tub 125

with a horizontal, perforated intake head disposed parallel to and below the axis of the drum but above the lowermost part of said drum.

- 5 5. In a washing machine, a water container, a perforated clothes container rotative therein, a water delivery pipe supported in the water container near the level of the top plane of the container and parallel thereto, a horizontal draw-off pipe beneath the level of the wash water on the side of
- 10

the clothes container remote from the delivery pipe and of substantially the same length as the clothes container, and a pump, to the outlet and inlet sides, respectively, of 15 which the water delivery and draw-off pipe are directly connected.

In testimony whereof I claim the foregoing as my invention, I hereunto append my signature at Chicago, Illinois, this 18th 20 day of July, 1919.

OGLESBY ALLEN, JR.
